UNITED STATES PATENT OFFICE.

ALEXANDER PALMROS, OF COLUMBUS, OHIO, ASSIGNOR TO THE JEFFREY MANUFACTURING COMPANY, OF COLUMBUS, OHIO, A CORPORATION OF OHIO.

MOTOR-CAR.

SPECIFICATION forming part of Letters Patent No. 760,556, dated May 24, 1904.

Application filed September 5, 1900. Serial No. 29,077. (No model.)

To all whom it may concern:

Be it known that I, ALEXANDER PALMROS, a citizen of Finland, residing at Columbus, in the county of Franklin and State of Ohio, have 5 invented certain new and useful Improvements in Motor-Cars, of which the following is a specification, reference being had therein to the accompanying drawings.

In order to make my invention more clearly 10 understood, I have shown in the accompanying drawings means for carrying it into practical effect without limiting my improvements in their useful applications to the particular construction which for the sake of illustration I have delineated.

In said drawings, Figure 1 is a side view of an electric locomotive embodying my invention. Fig. 2 is a plan view, partly in section, on line II II, Fig. 1. Fig. 3 is a side view of 20 the driving-wheels and the means for connecting them to each other and to the frame. Fig. 4 is a vertical section on line IV IV, Fig. 2.

Referring to the drawings, the main frame of the locomotive is composed of side bars or 25 frames A A' and end bars B B', fitting the former at the lower parts of their end faces and having inwardly-extending vertical flanges which lie within the side frames and are secured thereto by bolts a. These parts are 30 cast or otherwise constructed of great strength and weight to give the necessary traction-power.

The side frames are each formed with three or more spaces a' a' a' to accommodate the 35 suspension devices, hereinafter described, and between said spaces with vertical bars or columns a'. In the central space a' are situated vertical journal-box guides a' a', attached to or formed with the side frames and connected 40 with the bars a' by sills a'.

C C' C' are the axles of the supporting and driving wheels D D, D' D', and D'' D'', the end journals of which fit in and support boxes E E, E' E', and E'' E''. These boxes fit and may 45 move vertically on the guides a', as by flanges or ribs e on the boxes which engage corresponding grooves a' in said guides.

On the tops of the boxes are supported

springs F, located in the longitudinal planes of the frames A A' in the upper parts of the 50 spaces a' a' and secured by boxes, straps, or brackets f, which surround and are attached to the springs and are seated in recesses e' in the journal-boxes. At their ends said springs are connected with suspension-bars G G', as 55 by means of apertures f', provided in the springs, through which said bars G pass, and by cross-pieces, pins, or saddles g, fixed transversely in the bars and resting in recesses f' in the upper sides of the ends of the springs. 60 The said suspension-bars form a series, occupying portions of the spaces a' a', the end bars G' of which are connected with the main frame of the locomotive. Such a connection is conveniently effected by forming the frames 65 A A' with horizontal sills, braces, or bars a', connecting the main portions of such frames with the endmost guides a', and suspending the frames by pivot-pins g', passing through apertures a' in the bars a' and through the 70 lower ends of the bars G'. For greater strength and weight the frames A A' are formed with vertical longitudinal webs a' at the inner sides of the spaces a' a' and connecting the guides a' with the bodies of the frames, and to balance the strain on the pins g' the inner ends of the latter are seated also in apertures a' in the webs a'. The pins may be held in place 75 by heads on their outer and cotter-pins in their ends. The strains of the springs on the 80 bars G are transmitted from one to the other of said bars, as the strains vary and are equalized through movable connections. In the construction illustrated said connections comprise levers H, each having a substantially 85 central fulcrum on a transverse pin h, seated in an aperture a' in the side frame and secured in place by a cotter-pin h'.

The guides a' are connected at their lower ends by strap-bars a', secured to the frame 90 by bolts a'.

The wheels D D and D'' D'' are formed with flanges d, while the intermediate pair of wheels D' D' are without flanges and engage only the top surfaces of the rails.

The equalizing mechanism herein described

is much superior to any of the sorts heretofore known as concerns use with a motor-car or electric locomotive of the character of that herein presented. Cars like the present one 5 are intended for use in mines and similar places where the track is narrow, has many sharp curves, is irregularly laid, and frequently covered by obstructions, such as pieces of coal, rock, and the like. The cars 10 must be exceedingly short and the parts thereof very compactly arranged in small compass. They must be very heavy in order to provide sufficient traction. By employing the intermediate unflanged wheels D', I am enabled to 15 prevent the loss of traction efficiency, for if either of the driving-wheels D or D² should move up or escape from the rails its motion and the momentum of the neighboring part of the car is instantly transferred to the intermediate wheel and more or less to the other driver.

In another respect the car herein differs 20 from the earlier constructions employing equalizers—namely, in this that each of the axles and its pair of wheels are driven independently of the others, there being independent motors I, I', and I² geared to the axles, respectively. The motors are arranged as shown, those at I and I' extending in one direction 25 and that at I² in the opposite direction, whereby there is left an open chamber or space at I³ to receive the driver and wherein can be placed the several levers and operating devices, such as those for controlling the motors, the brake 30 mechanism, &c. As the central wheels D' D' are unflanged, the binding or cramping of the car when turning sharp bends is obviated.

What I claim is—

1. In a motor-car, the combination of the 40 body or main frame having the side frame-pieces formed with chambers to provide spaces to accommodate the wheel-suspension devices, such spaces being arranged within the outside and inside wall-faces of the frame-pieces, 45 and being also provided with journal-box guides, the axles extending from one of the said spaces to the opposite one, the wheels arranged in pairs upon the axles, and the equalizing mechanism interposed between the 50 wheels and the car-body and arranged in the said spaces, substantially as set forth.

2. In a motor-car, the combination of the 55 body having the side frame-pieces formed with chambers opening outward to provide spaces in which are mounted the wheel-suspension devices, such spaces being between the planes including the outside and inside wall-faces of the side frames, and being separated by the vertical bars a³, the journal-box guides arranged outside the said spaces, the axles extending from one space to the opposite one, the wheels arranged in pairs upon the axles, the journal-boxes arranged in the said guides 60 in which the axles are mounted, and the equalizing mechanism interposed between the 65

wheels and the car-body and arranged in the said spaces, substantially as set forth.

3. In a motor-car or locomotive adapted for use in mines, the combination of an inclosing main frame, the lower edges of the sides of which come close to the track, and which sides are formed with external chambers or recesses, the motor devices arranged within the inclosing frame, the traction-wheels, and the suspension devices arranged between the wheels and the frame and situated within the said recesses or chambers, substantially as set forth. 70

4. In a locomotive or motor adapted for use in mines, the combination of the main frame having the side frames formed with the vertical longitudinal webs a⁹, outside of which are arranged chambers or recesses, the motor devices arranged inside of the said webs, the traction-wheels, the supporting-axles of which pass through the said webs, and the suspension devices arranged between the traction-wheel axles and the frame and situated in the said recesses or chambers, substantially as set forth. 80

5. In an electric locomotive of the class described, the combination of a locomotive-frame, three axles, means for holding said axles permanently in parallel transverse planes, the unflanged wheels on the intermediate axle, the flanged wheels on the other two 90 axles, three independent motors, each connected with one of the axles and driving it independently of the others, and the equalizing-spring-supporting system interposed between the locomotive-frame and the said axles, 95 substantially as set forth.

6. In a motor-car the combination of the body or main frame, two outer driving-axles, two independent motors independently geared to said outer axles respectively, the two pairs 100 of the flanged driving-wheels one pair on each of said axles, the third axle intermediate of the two outer axles, the unflanged track-engaging wheels secured to the ends of the intermediate axle, the independent journal-boxes for the said axles mounted in vertically-disposed ways, and equalizing devices arranged between the journal-boxes of the flanged wheels and the journal-boxes of the unflanged wheels, substantially as set forth. 110

7. In a motor or locomotive, the combination of the main frame, the traction-wheels arranged in transversely-disposed pairs, one pair in advance of the other, independent vertically-movable journal-boxes for the wheel-axles, supporting-springs arranged between the journal-boxes and the frame, equalizing devices arranged between the springs of one pair of wheels and those of the other pair, and independent motors, one for each of the said 120 pairs of wheels, the wheels being unconnected, whereby they may be driven independently, substantially as set forth.

8. In a motor or locomotive, the combination of three pairs of wheels and their carrying- 130

- axles, independent vertically-movable supports in which the said axles are mounted, springs arranged between the several axles and the frame of the motor, equalizing devices 5 arranged between the two outer axles and the intermediate axle, and independent motors for each of the said axles and pairs of wheels, the wheels being non-coupled whereby the wheels may be driven independently and whereby 10 each pair of wheels is adapted to follow the track independently of the other pair, substantially as set forth.
9. In an electric locomotive of the class described the combination of a locomotive-body, 15 three axles, means for holding said axles in transverse planes permanently parallel to each other, a pair of track-wheels on each axle, the three track-wheels on each side of the locomotive being held permanently in the same 20 longitudinal planes, three electric motors each connected with an axle and driving it independently of the others, an equalizing-spring-supporting system for said axles interposed between them and the main frame, said equalizing system being at its ends flexibly connected to the main frame and pivoted to the 25

main frame at points between the intermediate axle and the two outside axles, substantially as set forth.

10. In an electric locomotive of the class described, the combination of the locomotive-body having an iron side wall formed with a series of cavities in its outer face, three axles mounted in the said body and held permanently in transverse planes parallel to each other, vertically-movable boxes for said shafts respectively, a spring bearing upon each box and arranged within one of the said cavities in the iron side wall, a pair of links for each spring arranged within one of the said cavities, and levers pivoted to the said wall on axes between the said boxes, the outer links of series being pivoted to the said wall and the intermediate links being respectively connected to the springs and to the levers, substantially as set forth. 30
